(57) **CLAIM**

The ornamental design for a personal grooming device, as shown and described.

DESCRIPTION

FIG. 1 is a perspective view of a personal grooming device showing our new design,

FIG. 2 is a front view thereof,

FIG. 3 is a rear view thereof,

FIG. 4 is a right side view thereof,

FIG. 5 is a left side view thereof;

FIG. 6 is top view thereof; and,

FIG. 7 is a bottom view thereof.

The broken lines are included for the purpose of illustrating portions of the personal grooming device that form no part of the claimed design.

1 Claim, 6 Drawing Sheets

FIG. 2

FIG. 3

FIG. 4

FIG. 5

FIG. 6

FIG. 7
